UNITED STATES PATENT OFFICE.

JOSEPH E. PERRAULT, OF BELMONT, MASSACHUSETTS, ASSIGNOR TO HOOD RUBBER COMPANY, OF WATERTOWN, MASSACHUSETTS, A CORPORATION OF MASSACHUSETTS.

DEMOUNTABLE FELLY-BAND FOR VEHICLE-WHEELS.

1,152,543.

specification of Letters Patent.

Patented Sept. 7, 1915.

Application filed December 14, 1914. Serial No. 877,182.

To all whom it may concern:

Be it known that I, JOSEPH E. PERRAULT, a citizen of the United States, residing at Belmont, Massachusetts, have invented certain new and useful Improvements in Demountable Felly-Bands for Vehicle-Wheels, of which the following is a specification.

My present invention relates to improvements in demountable felly bands for vehicle wheels and is designed more especially for use in connection with wheels of heavy trucks, adapted to receive and removably hold cushion or pneumatic tires.

Among the objects of the invention are to provide a felly band which may be readily applied and firmly held in position and which may be readily removed when it is necessary to demount the tire.

Another object is to provide a construction which may be economically manufactured.

An embodiment of my invention is illustrated in the accompanying drawing in which;

Figure 1 is a sectional perspective view, and, Fig. 2 is a perspective detail of one of the wedges.

Referring by reference characters to this drawing, the letter A designates a wooden felly and A', the permanent metal felly band of a motor vehicle wheel, such as ordinarily used.

B designates the removable felly band which is designed to carry the cushion or resilient tire, which may be of any desired construction.

The outer surface of the permanent metal felly band A' is made truly cylindrical but the inner or opposing surface of the band B' is made cylindrical only for a portion thereof, as indicated at b and is provided with outwardly flaring surfaces b', providing wedge-shaped spaces between itself and the permanent band A'.

On each side within these spaces I fit a plurality of wedges C which have a transverse section conforming to the wedge-shaped spaces between the bands A' and B and which are curved longitudinally to approximately the curve of the periphery of the wheel. These wedges as shown in Fig. 1, are applied from opposite sides to the wedge-shaped spaces between the inner and outer bands and are forced into position to firmly clamp the demountable felly band B and securely hold it in place by the

side flanges or rings D, which are drawn together by bolts E provided with suitable heads and nuts.

In practice, I make the wedges very short as compared with the entire periphery of the wheel and dispose them at distances apart approximately equal to or slightly exceeding the diameter of the bolt, so that the bolts may be passed through between the adjoining ends of the wedge-blocks. The inside circumference B' of the demountable band B also bears such a relation to the exterior circumference of the band A' as to leave space for the passage of the bolts and by this means, I avoid the necessity of boring or drilling any of these parts, thereby saving in cost of manufacture and producing strong and more durable results.

The wedge blocks have their wedge surfaces formed on a long angle so as to exert a great pressure when they are forced home by the tightening of the bolts and thus firmly hold the demountable band in position. At the same time however, as the wedges individually are very short, they may be removed with comparative ease when it is necessary to demount the band B. To facilitate the removal of the wedges, I provide them with cutaway portions c, leaving projecting ears c' so that after the flanges D and bolts E have been removed a suitable tool may be inserted into the space left by one of the bolts and its end engaged underneath one of the projections c' and the wedge quickly pried out, thus avoiding the necessity of doing any hammering, which mutilates the parts or is liable to break them. The wedge-blocks are of such dimensions as to cause a slight space to be left between the side rings or flanges D and the wedges of the demountable band B, so as to leave plenty of space for the wedges to be forced in until the band is held perfectly tight.

I have referred to the wedge-blocks as being curved longitudinally to approximately fit the curvature of the felly bands and the reason I use the word "approximately" is that due to the shortness of each wedge-block it is not necessary that this curvature should be exact. In fact, one of the advantages of my invention is that by using such a short wedge block, the same blocks may be used with wheels of different diameters. Wheels of motor trucks vary within determined limits and these limits are such

that wedge blocks of the type shown herein may be used with all diameters of wheels. This avoids the necessity of manufacturing a plurality of sizes of blocks and also avoids the liability of wedge blocks of the wrong size or shape being used, which would likely happen if wheels employing different sizes were being assembled in the same machine-shop or factory.

10 Having thus described my invention, what I claim is:

1. The combination with a permanent wheel felly band, of a removable felly band having oppositely inclined faces on its inner periphery, a plurality of wedge-blocks entered from opposite sides between said permanent felly band and removable felly band and spaced from each other, and side flange members connected together through the spaces between the adjoining ends of said wedge-blocks, substantially as described.

2. In combination a permanent felly band, a removable felly band concentric therewith and having oppositely inclined portions upon its inner periphery, a plurality of wedge blocks entered between said permanent felly band and removable felly band, circular side clamping rings extending over the exposed ends of all of said wedge-blocks on each side and bolts connecting said side

rings and passing through the spaces between the ends of the wedge blocks, substantially as described.

3. The combination with a permanent 35 wheel felly band, of a removable felly band having oppositely inclined faces on its inner periphery, a plurality of wedge blocks entered from opposite sides between said permanent felly band and removable felly 40 band and spaced from each other, and clamping rings connected to each other through the spaces between the adjacent ends of said wedge blocks, each of said wedge blocks having a lug or extension for 45 engagement with a prying tool, substantially as described.

4. In combination a wheel felly band and an outer removable band, one of said bands having oppositely inclined faces, a plurality 50 of wedge blocks entered from opposite sides between said bands and spaced from each other, each of said wedge blocks having a lug or extension for engagement with a prying tool, and removable means for clamp- 55 ing said wedge blocks in position.

In testimony whereof, I affix my signature in presence of two witnesses.

JOSEPH E. PERRAULT.
